UNITED STATES PATENT OFFICE.

HENDERSON WILLARD, OF GRAND RAPIDS, MICHIGAN.

ACOUSTIC TELEPHONE.

SPECIFICATION forming part of Letters Patent No. 238,740, dated March 8, 1881.

Application filed November 19, 1880. (Model.)

To all whom it may concern:

Be it known that I, HENDERSON WILLARD, a citizen of the United States, residing at the city of Grand Rapids, in the county of Kent, and State of Michigan, have invented 5 certain Improvements in Acoustic Telephones, of which the following is a specification.

This invention relates to acoustic telephones in which a line of wire connects two vibrating 10 diaphragms, either of which may receive or transmit sound.

The said invention consists, principally, in the combination, with each diaphragm, of a mouth-and-ear piece having its rear face in 15 contact at all points with the front of said diaphragm, in order to insure clearness and accuracy of sound.

It also consists in constructing each mouth-and-ear piece with an inwardly-flaring passage 20 or chamber having straight sides inclined at an angle, which will cause all sound-waves received therein from the diaphragm to be reflected forward through the open front of the instrument without returning to the diaphragm 25 or the neighborhood thereof.

It consists, finally, in the special devices for supporting the connecting-wire, and in certain other improvements hereinafter set forth.

In the accompanying drawings, Figure 1 30 represents a vertical section through one of the transmitting or receiving instruments, arranged with its mouth-piece upward; and Fig. 2 represents a side view of a part of the connecting-wire and the devices for supporting 35 the same.

A designates one of the receiving or transmitting instruments, (it being adapted to either use,) which consists of a case inclosing a broad rear sound-chamber, a mouth-piece or rear-piece, 40 B, and a diaphragm, C, that separates said chamber from the interior of said mouth-piece. Said case preferably consists of a front part integral with said mouth-piece, and a rear part, A', secured to said front part by screws 45 h h. A transmitting or connecting wire, C', is attached at one end to one of said diaphragms and at the other end to the other, the attachment being made in each case by means of a button, d, on the front of the diaphragm, and an eye, O, at the rear of the latter, said eye having a shank, which passes

through said diaphragm and screws into said button.

The general construction of the telephone, as above indicated, is not broadly new; but 55 hitherto there have been spaces, chambers, or recesses interposed between the front of the diaphragm and the rear portion or base of the mouth-piece. Now the said mouth-piece becomes an ear-piece when the instrument is 60 used for receiving a message, and there ought to be perfect clearness, distinctness, and purity of tone in the messages received through it. Such air chambers, spaces, or recesses between any part of the diaphragm and the rear wall 65 of the mouth-piece will inevitably cause a certain inequality and unreliability in the vibrations of the diaphragm and a partial deadening of tone and confusion of sound. To obviate this serious defect I have caused the rear 70 wall or base, b, of my mouth-piece (it is also the front wall of the casing A) to fit at all points squarely against the front face of diaphragm C, said diaphragm being attached near its periphery to said wall b by tacks n or 75 other convenient fastenings. When the sound-waves passing through wire C' reach diaphragm C they are transmitted, by the central portion of the latter, to the space or passage within the mouth-piece without any loss of 80 tone or confusion of sound. The wall b affords at all points, except within the central opening, a solid brace or backing for said diaphragm.

The construction of my mouth-piece is another important feature of my invention. This mouth-piece (or ear-piece) consists of an outwardly-flaring part, f'', and an inwardly-flaring part, f''', which form a shell or casing for two communicating chambers or passages, f/f', 90 which have the shape of truncated cones placed with their lesser ends together, so as to form a neck, f''''. The outer chamber, f, has a wide flare, so as to accommodate a person's mouth or ear readily and fully. The inner one flares 95 less, the sides having such an inclination that the waves of sound thrown against the same, by the action of the diaphragm in receiving, will not be reflected back to said diaphragm nor across from side to side, but out of the instrument through the neck f''''' and the chamber or passage f. This avoids the confusion 100

and indistinctness of sound due to vibrations from side to side of the ear-piece B and back toward diaphragm C, which must inevitably arise when the chamber corresponding to f' has curved walls, or even straight walls of too great an inclination. The curved walls are, however, more objectionable than these last, since they tend to concentrate or focalize the sound-waves on the center of the dia-
phragm.

In sending a message a part of the sound-waves caused by the voice will be reflected by the inclined sides of space f through neck f''' against the inner face of the wall of f' , where-
15 by they will again be reflected in converging lines on the center of the diaphragm, so as to strengthen the sound without confusing it. Another portion of the sound-waves will pass directly through neck f'''' to diaphragm C with-
20 out any reflection whatever. Said diaphragm consists of two wooden strips or veneers, a and a' , arranged with the grain of one crossing that of the other. This cross-grain arrangement lessens the liability to warp or split. Two
25 strips, united as shown, give greater elasticity and resonance than a single piece of equal thickness. I thus combine in my diaphragm the highest degree of durability and resonance consistent with a given quantity of the proper ma-
terial.

To prevent sagging of the line-wire C', and impediment of longitudinal vibrations therein, and to maintain equality of tension at all points, I employ a number of supporting-
35 springs therefor, hung at suitable intervals, and having the construction shown in Fig. 2. Each of these springs has a central eye, y , and two arms, s s' , that extend therefrom in oppo-

site directions, the whole being formed from one bar of spring-wire. Eye y is suspended 40 by a wire, l , from any suitable fixed device, and the ends of arms s s' are connected, by suspending-wires x x' , to two different points on line-wire C', said line-wire being free, however, to slide through eyes or loops formed on the 45 lower end of said suspending-wires. Arms s s' tend constantly to rise into the position in-
dicated in dotted lines, thus lifting said wire and maintaining it everywhere under equal tension. If the spring-support were at one 50 point of the wire only the angle formed there-
in would necessarily be more acute than those formed by my double spring-support above described, and the transmission of the sound would be more or less impeded thereby. 55

Having thus described my invention, what I claim is—

1. The combination of a diaphragm for trans-
mitting and receiving sound with the rear face 60 of the base of the mouth-and-ear piece, the greater part of said diaphragm being in contact with said rear face, for the purpose set forth.

2. In combination with a diaphragm for re-
ceiving and transmitting sound, a mouth-and- 65 ear piece having its interior formed of two straight solid communicating conoidal cham-
bers, substantially as set forth.

3. A spring-bar, forming loop y , and arms s s' , in combination with line-wire C' and sus- 70 pending-wires l x x' .

HENDERSON WILLARD.
